WASTE RECEPTACLE

Benjamin Gottheim, Brooklyn, N. Y.

Application December 14, 1937, Serial No. 179,690

7 Claims. (Cl. 206—63.5)

This invention relates to waste receivers and more specifically to a receiver for use by the medical and dental professions in the disposal of used cotton pellets, cotton rolls and other germ laden waste materials used in the treatment and extraction of teeth.

At present it is the custom of the dental profession to dispose of cotton pellets used in the treatment of the teeth, gums and jaws, by inserting the same through the slit top of a closed carton. Whereas a waste carton should be disposed of for sanitary reasons immediately after the treatment of a patient, the attending dentist may forget to dispose of a used one and substitute a fresh one, or for economic reasons, he may deliberately employ the same waste carton until the same has become filled, and during which time a number of patients have been treated. This condition is inductive for the spread of infections and disease from one patient to another. In order to dispose of a waste cotton pellet, it is necessary that the same, while still being held by the jaws of a tweezer or like dental instrument, must be forced through the slit in the top of the carton. In forcing the waste cotton pellet through the slit, the tweezers or other instrument comes in contact with the walls of the slit, and immediately, this area absorbs the germ laden fluids such as blood, pus, and saliva, which by reason of the use of the carton in the treatment of a previous patient, may pick up germs which are then transferred to the next patient being treated. A dentist may be treating an infected tooth or socket or gum area in the mouth of a patient, and may also treat uninfected teeth, or socket in the mouth of the very same patient during the same sitting. In using the closed carton waste receiver there is a constant danger of carrying the germs from the diseased area by contact with the waste receiver to the healthy area.

When large pieces of waste material such as cotton waste, cotton rolls saturated with germ laden fluids such as blood and pus, are forced through the slit of the closed receiver used today, these fluids usually spatter all over the bracket table, on the instruments and at times over the patient and dentist. This is unsanitary and dangerous.

The receiver because of its closed top requires the dentist to dispose of large waste materials by walking to the floor waste can away from the dental chair and depositing it there. This procedure is tiring, inconvenient, and unsanitary, as drippings from saturated waste receiver are

often spattered over the patient and floor until carried to the floor waste can. Often this waste is accidentally thrown on the floor. This closed carton receiver must of necessity be forced tightly into conventional holders with tapering sides and forced up through the broad bottom of the holder, so that the cross slit is on the top. To discard this used carton it is the common practice for the dentist to force it out with his fingers, which must touch the germ saturated top of the receiver. Thus the importance of individual waste cartons for the respective patients is essential in the prevention of spreading infections and diseases from one patient to another, but as above pointed out this sanitary requirement is not strictly adhered to.

One of the principal objects of this invention resides in a waste receiver for dentists which may be sanitarily used in the disposal of cotton pellets during the treatment of more than a single patient, if necessary, without the danger of transmitting infection from one patient to another, should the dentist forget to change the waste receiver after each patient as should be done, and which feature is accomplished by providing individual openings in a paper receptacle for successive use and through which the germ laden pellet which clings to the tweezers and cannot be dropped into the waste receiver from the open top may be inserted and stripped free of the jaws of the tweezers upon withdrawal of the jaws of the instrument from the opening.

Another feature of the invention is to provide a paper dental waste receiver in which the walls of the cotton pellet receiving openings are mutilated as they are used to visibly indicate to the dentist that such opening has been used and for sanitary reasons should not be used again, thus the next unused opening is chosen, and when the walls of all the openings become mutilated, the waste receiver and its contents are disposed of and the same replaced by a fresh one.

Another feature of the invention is the provision of a dental waste receiver having an open top for the reception of cotton rolls, gutta-percha, plaster, extracted teeth and other heavier pieces of waste which readily release themselves from the tweezers or other holder instrument, the side walls of the receiver having the aforementioned openings to receive and free other waste material which may have a tendency to cling to the jaws of the holder instrument.

Another feature is that of providing an open top dental waste receiver as distinguished from the closed carton type of receiver is that the

waste contents thereof being in plain view of a dentist and a patient to be treated, the dentist will be induced to provide a fresh receiver for each patient.

5 A still further feature of the invention is to provide a dental waste receiver which is of such inexpensive construction as to enable individual use of the receiver without economic hardship to the dental profession.

10 Other objects of the invention will appear as the following specification is read in conjunction with the accompanying drawing, in which,

15 Figure 1 is a perspective view of my improved dental waste receiver in position of use, one of the waste receiving openings being shown mutilated by previous use thereof.

Figure 2 is a vertical longitudinal sectional view.

20 Figure 3 is a plan view of the blank from which the waste receiver is formed.

25 Referring to the drawing by reference characters, the numeral 10 designates my improved dental waste receiver in its entirety which is folded into box form from a single blank of cardboard A as illustrated in Figure 3 of the drawing. The blank A includes a rectangular area scored on the substantially equi-distantly spaced parallel lines 11, 12 and 13 to provide four identical side walls 14, 15, 16, and 17. Inwardly foldable bottom flaps 18 and 19 are connected to the bottom of the side walls 15 and 17 respectively, while integral with the side wall 14 is an inwardly folding bottom wall 20 which has a locking flap 21 co-extensive therewith. An attaching glue flap 22 extends from the outer side of the side wall 14 and when the side walls are folded on the respective fold lines 11, 12, and 13, the flap is folded on the line 23 so as to lie flat against and be glued to the side wall 17. When 40 the side walls have been secured in the manner just described, it is possible to flatten out the partially set up receiver for the same will collapse on the fold lines 11, 12, 13 and 23. For convenience the receiver will be sold in collapsed form and set up for use as needed. To complete 45 the setting up of the receiver, it is only necessary to fold the flaps 18 and 19 inwardly, after which, the tongue flap 21 is folded into the receiver body as best seen in Figure 2. The folding of the bottom flaps provides a bottom wall for the receiver and maintains the side walls in fixed upstanding position.

50 The receiver body is open at its top as at 24 and the top edge of each side wall is provided with a series of spaced V shaped notches 25 to be used for a purpose presently to be explained.

55 Each side wall is provided adjacent its top edge with a pair of round openings 26 of a size to freely enable the insertion of the jaw end of a dental tweezers when gripping a cotton pellet or other like germ laden dental waste. Extending downwardly from each opening 26 is a narrow V-shaped slit 27. The openings 26 are on the 60 same horizontal plane and provide a row of spaced waste receiving openings around the four sides of the receiver body.

65 In use, the box-like receiver body 10 is firmly supported upon a dentist's bracket table by fitting the lower portion of the same into the socket or recess 28 of a conventional holder device 29. The waste receiver 10 is of such height relative to the height of the holder device 29, that the openings 26 and slits 27 are disposed well above 70 the top of the holder device.

In practice, a fresh waste receiver is used for each patient, but should the dentist or nurse forget to change the used waste receiver, no damage will occur such as the likelihood of spreading disease, or the carrying of germs from the waste 5 receiver to the patient, as the waste is ordinarily dropped in from the open top and the individual openings are used only in the case of small clinging waste. After an opening 26 has been used to facilitate the depositing of a piece of dental waste 10 into the receiver, that opening is never used again for it is mutilated to visibly distinguish the same from an unused opening, whereupon the dentist 15 may know at a glance which opening is sanitarily safe to use in the disposal of other waste material.

Assume that it is desirous to dispose of a cotton pellet or like waste material C held by the gripping jaws of the tweezers B. The jaw end of the tweezers B is inserted through an unused opening 26 to dispose the waste material C within the receiver body whereupon the dentist moves the tweezers downwardly so that the jaw ends 20 forcibly enters the slit 27 as shown in Figure 2 of the drawing. Then he releases his grip upon the clamping jaws of the tweezers which are withdrawn through slit 27, causing mutilation or deforming of the walls of the slit as shown in Figures 1 and 2, and at the same time, any waste material which has a tendency to cling to the 25 tweezers although the jaws of the tweezers have been released, is stripped from the tweezers or other instrument and drops into the receiver.

Larger germ laden waste such as cotton rolls, 30 gutta-percha, plaster, and the like may be deposited into the receiver through the open top thereof and are of such nature as to free themselves from the tweezers or other holder instrument. However, should any of the larger waste material cling to the tweezers, the same may be 35 stripped therefrom by placing the instrument in one of the notches 25 or between two or more notches and drawing the instrument outwardly whereupon the waste will be freed and drop 40 within the receptacle. It is possible to detect 45 which of the notches have been used, for the walls thereof may become stained or discolored by contact with the jaw ends of the instrument or by contact with the germ laden waste substance. The notches are also used as instrument wipers 50 or cleaners. By running the moist part of the tweezers or other instrument back and forth, the instruments are cleaned of fluid such as blood, pus or medication.

55 After the openings 26 and notches 25 have been used in the stripping of dental waste substances from the holder implement, the receiver 10 is removed from the holder 29 by lifting the receiver out of the holder easily with the tweezers, or by inserting an instrument through one of the 60 individual holes and disposed of without a dentist's finger touching it, while a fresh receiver is placed in the holder 29.

65 While I have shown and described what I consider to be the preferred embodiment of my invention, I wish it to be understood that such changes and alterations as come within the scope of the appended claims may be resorted to if desired without in any way departing from the spirit 70 of the invention.

Having thus described the invention, what I claim as new and desire to secure by Letters Patent of the United States is:

75 1. A dental waste receiver comprising a cardboard receptacle body open at its top to receive

5 dental waste materials, and spaced notches provided in the top edges of the side walls of said receptacle body to facilitate the stripping of waste materials from a dental tweezers or like holder instrument in instances where the waste material will not freely drop from the holder instrument.

10 2. A sanitary dental waste receiver comprising a cardboard receptacle body open at its top to freely receive dental waste materials when dropped thereinto, and spaced V shaped notches provided in the top edges of the side walls of said receptacle body into which the holder end of a dental holding instrument may be seated and subsequently pulled outwardly to effect the 15 stripping of any waste materials therefrom which may have a tendency to cling to a holding instrument.

15 3. A sanitary dental waste receiver comprising a cardboard receptacle body open at its top to freely receive dental waste materials when dropped thereinto, and closely spaced stripper elements provided on and rising upwardly from the top of the side walls of said body between which the holder end of a dental holding instrument may be inserted and subsequently pulled outwardly to effect a stripping of any waste materials therefrom which may have a tendency 20 to cling to a holding instrument.

25 4. A sanitary dental waste receiver comprising a single blank of cardboard which is cut, folded and secured to provide a receptacle body having a closed bottom and an open top whereby waste materials held by a dental instrument may be freely deposited into said body by dropping the same thereinto, and spaced upstanding stripper elements on the top edge of the side walls of said body whereby waste materials having a 30

tendency to cling to a dental instrument may be scraped free into said body by drawing the instrument outwardly across the top edge of said body in contact with one or more of the stripper elements.

5 5. A sanitary disposable dental waste receptacle comprising a cardboard receptacle body closed at its bottom and open at its top, the top edge of said body being serrated to provide spaced stripper elements for individual use in the stripping 10 of clinging waste into said body from a dental instrument.

15 6. A sanitary dental waste receiver comprising a single blank of cardboard having a rectangular side wall forming area scored on three spaced parallel score lines to divide the same into four side walls, the top edge of said blank being provided with groups of closely spaced substantially V-shaped notches respectively arranged intermediate the ends of the said score lines, a foldable glue flap integral with one of the side walls for infolding and glueing to the next adjacent side wall when the blank is folded on the score lines to set up position for use, and inwardly foldable bottom forming flaps integral with certain of the bottom edges of certain of said side walls for forming a bottom wall.

20 7. A sanitary dental waste receiver comprising a single blank of cardboard which is cut, scored, folded, and secured to provide angularly related upstanding side walls and a bottom wall, and a group of closely spaced substantially V-shaped notches on the top edge of each side wall substantially as and for the purpose specified.
